UNITED STATES PATENT OFFICE.

NATHANIEL T. WHITING, OF LAWRENCE, MASSACHUSETTS.

IMPROVEMENT IN BUTTON-HOLES FOR PAPER COLLARS.

Specification forming part of Letters Patent No. 55,753, dated June 19, 1866.

To all whom it may concern:

Be it known that I, NATHANIEL T. WHITING, of Lawrence, in the county of Essex and State of Massachusetts, have invented a new and useful Improvement in Button-Holes for Paper Collars, of which the following is a full, clear, and exact description, reference being had to the accompanying drawings, making part of this specification, in which—

Figure 1 represents the inner side of a full-sized collar, provided with my improved button-holes. Figs. 2 and 3, detached end portions of the same, with a button, B, passing through the slots *c* at each side of the button-hole *A* in Fig. 2.

In my said invention the collar C may be of any convenient form or size, and made to stand up or to turn down over a cravat, as are the ordinary collars.

The button-holes *A* are cut through the substance of the paper, one of them at or near the middle of the collar and one near each end, as is usual.

To prevent the button-hole from being torn and destroyed by forcing the button sidewise through the hole, I provide a lateral slot or opening, *c*, at each side of the button-hole *A*, said slots being sufficiently wide to admit the thickness of a common button, and long enough, from the extremity *v* of one slot to that of the other slot, to allow any common button to pass freely through the same and not tear or injure the paper of which the collar is made.

In the use of my improved button-hole for paper collars the button *B* may be easily pushed through the slots *c*, as shown in Fig. 2, when

the eye of the button will move readily forward in the button-hole *A* and allow the button to come out onto the face or outer side of the collar in its proper position.

In detaching a collar from the button or buttons it is only necessary to guide the button into the slots *c* and move it gently forward or backward, when it will slide freely through the slots *c* and the button-hole *A*, and the collar is detached.

My improved button-hole is intended to be applied to paper wristbands as well as collars, and is equally or more useful in the former than in the latter.

I sometimes make my improved button-holes with an incision or cut, *d*, at each side, as shown in Fig. 3, instead of removing a portion of the paper to form the slots *c*.

I am aware that a button-hole for paper collars has been patented by B. F. Porter, of Nashua, New Hampshire, consisting of a semi-circular opening at one end of the button-hole and a lip or fly arranged in connection therewith.

I do not claim having invented the equivalent, in principle or action, of the above-named button-hole; but

What I do claim as new, and desire to secure by Letters Patent, is—

The lateral slots *c* or cuts *d d*, combined with the button-holes *A*, substantially as and for the purpose specified.

NATHANIEL T. WHITING.
